UNITED STATES PATENT OFFICE.

HENRY C. STRUCHEN, OF WHITE BEAR, MINNESOTA.

WINDOW-GUARD.

1,168,577.

Specification of Letters Patent. Patented Jan. 18, 1916.

Application filed July 27, 1914. Serial No. 853,346.

To all whom it may concern:

Be it known that I, HENRY C. STRUCHEN, a citizen of the United States, residing at White Bear, in the county of Ramsey and 5 State of Minnesota, have invented new and useful Improvements in Window-Guards, of which the following is a specification.

My invention relates to improvements in window guards particularly adapted for use 10 in asylums for the feeble minded and insane.

Window guards of the type commonly employed in such institutions are frequently shaken or rattled by the inmates, which habit results in unnecessary wear and causes 15 nerve-racking noises about the premises. The locking devices for these guards, are usually exposed or accessible from within and as a result are tampered with by the inmates through curiosity or in an attempt to 20 escape. Such locking devices are also generally difficult to manipulate and are often rendered totally inoperative by meddlers.

It is the object of my invention to provide 25 a strong and durable window guard having an easily operated locking device adapted to firmly secure the guard and lock from vibrating when in closed position, and so arranged that the locking device is normally concealed and guarded in the structure of 30 said device.

In the drawings Figure 1 is an elevation 35 of my improved window guard as applied to a window opening; Fig. 2 is an enlarged fragmentary sectional view taken longitudinally through the free side of the window; Fig. 3 is an enlarged sectional view, partly broken away, taken on a line 3—3 of Fig. 1; Fig. 4 is a detail sectional view taken on the line 4—4 of Fig. 2; Fig. 5 is a detail sectional view taken on the line 5—5 of Fig. 1; and Fig. 6 is a perspective view in detail of 40 the upper right hand corner of the window as seen in Fig. 1.

Referring to the accompanying drawings, 45 I have used the reference letter A to indicate the window, B the jamb to which the window is hinged and C the jamb to which said window is locked when closed. The window jamb B is a vertical channel bar, 50 adapted to be secured to a window casing,

by screws 10 or the like, with the flanges 11 of said bar abutting against said casing. The jamb C as shown is made up of a vertical channel bar together with a bumper plate or window-stop 14 secured to the outer 55 flange 15 of said channel bar and an abutment bar 16 secured within said channel adjacent to the inner flange 17 thereof. The web 12 of said channel bar is seated against and secured to the side of the window casing 60 by suitable means such as screws 13.

The window A consists of an iron frame carrying a heavy metal screen a. This frame is composed of a top piece 20, bottom piece 21 and side pieces 22 and 23 all of said parts being of channel iron with the flanges thereof turned outwardly, with reference to the center of the window. The webs of these channel bars are perforated to receive the ends of the wires of the screen which are 70 bent within said channels. A reinforcing band 24 is secured by bolts 25 around the top, bottom and side pieces 20, 21 and 22 of the window thus covering the channels there-in. A similar reinforcing band 26 is secured 75 to the side channel bar 23. Horizontal bars 27 are clamped on opposite sides of said screen a to reinforce the same at the center.

The side piece 22 of the window is attached to the jamb B by hinges 28 which 80 permit the window A to swing inwardly from the casing.

Novel locking mechanism is provided for securing the window A in closed position, which consists of a rotatable rod 29 incased 85 within the side channel 23 and having latch bolts 30 and an operating handle 31 integral therewith. The flange 15 of the channel bar 23 and the bolts 32 which secure the band 26 to said bar form the casing in which 90 said rod turns. The side of the window A, consisting of the channel bar 23 and reinforcing band 26, is cut away at 23^a, 23^b and 26^a and the window jamb C is also cut away at 14^a and 15^a to permit the movement of 95 the handle 31 in said window and the movement of the bolts 30 into and out of said window jamb from the position shown in solid lines to that shown in dotted lines in Fig. 3. The latch bolts 30, as shown, are 100

three in number, one being arranged on the rod 29 opposite to the handle 31, while the other two are formed in similar relation to the rod 29, but at the opposite extremities of the channel bar 23. Movement of the latch bolts to the position shown in solid lines in Fig. 3 presses the same against the abutment bar 16 of the jamb C and clamps the free side of the window against the stop 14 of the jamb C, thereby rigidly securing the window in closed position and preventing vibration. Movement of said latch bolts to dotted line position, as shown in Fig. 3, removes the same from the jamb C and permits the window to be swung inwardly.

It will be noted that when the window A is closed the rod 29 and latch-bolts 30 are incased and inaccessible. I have also incased the handle 31 to guard the same and secure it in position to hold the latch-bolts 30 in unalterable engagement with the bar 16 of the jamb C. The housing D for said handle includes a frame, consisting of a U-shaped channel bar 33 and a portion of the frame channel 23 to which it is secured in any suitable manner, said U-shaped bar being also secured to ends of the screen wires. A side plate 34, notched at 34^a to receive the middle latch-bolt 30, is permanently secured to one face of the U-shaped bar 33 and the closure or guard shutter 35 for said casing is furnished with hinges 36, by which it is hung to the bar 33. A spring lock 37 of ordinary design is riveted near the upper edge of said closure to catch within the upper flange 33^a of said channel bar 33 and hold said closure shut. The end of the handle 31 is preferably turned upon itself as shown in Fig. 3.

The resiliency of the handle 31, rod 29 and latch-bolts 30, which are integral with one another, is such that when the closure is forced against the handle and locked, the latch-bolts are forced against the abutment bar 16, thus immovably holding the window against the stop 14.

In use, the window when locked is firmly clamped in closed position, the locking mechanism thereof being concealed and inaccessible to those without a key. To open the window, the spring lock 36 on the closure 35 of the housing D is unlatched by a key and said closure is lowered. The handle 31 is pulled outward to turn the latch-bolts 30 away from the window jamb C and the window is free to open. A marked advantage of this window over others in common use is due to the ease with which it may be closed and locked. It is only necessary to swing the window to position where the latch-bolts 30 strike the abutment bar 16 and when said handle is pressed within the housing D the window A is closed, the upper, lower and central portions of the frame

23 being drawn snugly against the window- 65 stop on the jamb C.

It is obvious that my device may be applied to doors as well as windows, that the jamb C may be formed of a single piece of metal if desired and that other changes may 70 be made in my preferred form, without departing from the spirit of this invention.

Having described my invention what I claim as new and desire to protect by Letters Patent is:—

1. In a window locking device, a swiveled rod concealed within the window structure and formed with a handle and latch bolts rigidly attached thereto, a housing carried upon the window to inclose said handle, a 80 stop and an abutment located on the window frame and arranged to form a recess between them which is adapted to be covered by the window when closed, said bolts being designed to enter said recess and engage 85 said abutment to clamp the window against said stop.

2. The combination of a stop and an abutment located on a window frame, a plurality of swinging latch bolts carried upon a 90 window, a revoluble rod on the window for shifting said latch bolts to press the same against said abutment and secure the window against said stop, a handle on the rod for turning the same and a guard shutter adapted to impinge against said handle and hold it in locked position.

3. In a window locking device, a stop and an abutment located upon a window frame, latch bolts carried upon a window, said stop 100 and abutment being arranged to form a recess adapted to receive said bolts and also adapted to be covered by said door, a handle connected with said latch bolts to turn the same and press them against the abutment, 105 whereby the window may be clamped against the stop, and means carried by the window for completely inclosing said handle and holding the same in locked position.

4. In a window locking device, a stop and 110 an abutment upon a window frame, a rod adapted to be revolvably mounted upon a window, latch bolts integral with said rod, a handle on the rod for turning the same to press said bolts against said abutment and 115 thereby clamp the window against said stop, a housing for the handle, carried by the window, said housing having an opening therein through which the handle may pass and a closure for said opening, impinging 120 against the handle to confine the bolts in clamped position.

5. In a window locking device a stop and 125 an abutment located on a window frame, a rod adapted to be revolvably mounted upon a window and having latch bolts and a resilient handle formed thereon, said handle being adapted to turn said rod and press the

latch bolts against said abutment, whereby the window may be clamped against said stop, a housing for the handle carried by the window and a closure for said housing 5 arranged to forcibly secure the handle therein and guard the same when the window is closed.

In testimony whereof, I have signed my name to this specification in the presence of two subscribing witnesses.

HENRY C. STRUCHEN.
